UNITED STATES PATENT OFFICE.

JOHN HARRISON, OF MALAD CITY, IDAHO.

GATE-HINGE

1,035,584.

Specification of Letters Patent Patented Aug. 13, 1912.

Application filed March 4, 1912. Serial No. 881,324.

To all whom it may concern:

Be it known that I, JOHN HARRISON, a citizen of the United States, residing at Malad City, in the county of Oneida and State of Idaho, have invented certain new and useful Improvements in Gate-Hinges, of which the following is a specification.

This invention relates to gate hinges and more particularly to a hinge which is primarily designed for use on farm gates the object being to support the gate for free swinging movement over uneven ground and at the same time relieve the hinge post of the weight of the gate.

Another object of the invention resides in the provision of a hinge of the above noted type which is simple and inexpensive in construction, and highly efficient and durable in practical use.

With these and other objects in view, this invention resides in the novel features of construction, formations, combinations and arrangements of parts to be hereinafter more fully described, claimed and illustrated in the accompanying drawings, in which—

Figure 1 is a side elevation of a gate illustrating the application of the hinge. Fig. 2 is a top plan view, and Fig. 3 is an enlarged perspective view of the hinge. Fig. 4 is a perspective view of the modification of the loop carried at the upper side of the gate for engagement with a pintle.

Referring in detail to the drawing 5 designates a gate which may be of any preferred construction, said gate being mounted, at one end, for swinging movement upon the hinge post 6. The free end of the gate is supported for movement by means of a 40 caster wheel 7 which is secured to the lower edge of the gate.

A lower hinge 8 of any approved form connects the gate to the post 6. My improved hinge which forms the subject matter of the present application, is applied to the upper end of the hinge post and gate, and consists of a pintle rod 9 which is securely fastened by suitable screws, bolts or analogous means to the side of the post adjacent the gate. This rod is laterally offset as indicated at 10, the upper portion 11

thereof extending above the post 6. The end of this latter portion of the pintle rod is bent at a right angle to form a stop 12 for the purpose which will more fully appear in the following description.

To the upper hinged end of the gate a strap plate 13 is rigidly secured at its ends, said plate being bent upon itself to provide a horizontally disposed elongated loop 14 which extends laterally from the gate toward the post 6 and is adapted to receive the upper portion 11 of the pintle rod. The space between the parallel portions of the strap plate forming the loop is sufficient to permit said loop to move freely thereon while the stop 12 prevents the loop from lifting off of the pintle.

From the foregoing the construction and operation of my improved hinge will be clearly understood. The gate may move easily at its free end over an uneven ground surface without liability of breaking the hinges, while the hinge post 6 is relieved of the weight of the gate thereby greatly contributing to the durability and efficiency of the gate as a whole. The invention is simple in construction, may be produced at small cost and can be applied to the ordinary farm gate without necessitating the employment of skilled labor.

While I have shown and described the preferred embodiment of the invention it will be understood that the same is susceptible of considerable modification without departing from the essential feature or sacrificing any of the advantages thereof.

The modification illustrated in Fig. 4 is a loop which is applicable to any sized gate and is advantageous over the preferred form in that the preferred form may be applied only to stanchions of a fixed width. The construction comprises a loop 14^a formed after the manner of the loop 14 in the preferred form, having one arm 15 thereof extending in direct alinement while the opposite arm 16 is offset inwardly and rests flush against the outer surface of the arm 15, the arm 15 being of greater length than the arm 16. These arms are attached by a single fastening means piercing both arms and projecting into the post of the gate.

Having thus fully described this invention, what I claim as new and desire to secure by Letters Patent is:

The combination with a gate end and a hinge post for said gate, of a pintle secured to said post and having an offset portion extending above the upper end thereof, and a laterally extending elongated loop secured to said gate and horizontally and vertically 10 movable on the offset portion of the pintle,

the upper end of said pintle being bent to 15 form a stop to limit the upward movement of said loop.

In testimony whereof I affix my signature in presence of two witnesses.

JOHN HARRISON.
